CLAIM

The ornamental design for container for animals, as shown and described.

DESCRIPTION

FIG. 1 is a perspective view of container for animals showing the new design;

FIG. 2 is another perspective view thereof;

FIG. 3 is a front elevational view thereof, the rear elevation view being identical thereto;

FIG. 4 is a right side elevational view thereof, the left side elevation view being identical thereto;

FIG. 5 is a top plan view thereof; and,

FIG. 6 is a bottom plan view thereof.
